UNITED STATES PATENT OFFICE.

ARTHUR WM. SKOWBO, OF ARMSTRONG, IOWA.

SHAVING-BRUSH.

1,143,451.

Specification of Letters Patent. Patented June 15, 1915.

Application filed January 9, 1915. Serial No. 1,388.

To all whom it may concern:

Be it known that I, ARTHUR WM. SKOWBO, a citizen of the United States, residing at Armstrong, in the county of Emmet and State of Iowa, have invented certain new and useful Improvements in Shaving-Brushes; and I do hereby declare the following to be a full, clear, and exact description of the invention, such as will enable others skilled in the art to which it appertains to make and use the same.

This invention relates to new and useful improvements in shaving brushes, and has for its principal object to provide a fountain shaving brush which is so constructed as to prevent waste of soap.

Another object of the invention is to provide a brush in which the soap is contained in the handle and is fed into the bristles of the brush only when in use and it is necessary that the brush be soaped.

A further object of the invention is to provide a novel form of soap container and feeding device for the brush which operates with a minimum amount of energy and which will not under any circumstances leak or become clogged or gummed.

With these and other objects in view, the invention consists in the novel combination and arrangement of parts which will be fully set forth in the following specification and accompanying drawings, in which,

Figure 1 is a view in elevation of a shaving brush constructed in accordance with this invention showing the same entirely inclosed in its cover. Fig. 2 is a longitudinal sectional view of the brush showing the same with the cover removed. Fig. 3 is an end view in elevation of the bristle cover, Fig. 4 is an end view in elevation of the handle showing the cover therefor removed, Fig. 5 is an end view of the bristle holder, and Fig. 6 is a detail sectional view of the valve.

Referring now to the drawings by characters of reference, the numeral 1 designates as an entirety a shaving brush constructed in accordance with this invention comprising a cylindrical casing 2 which is of the same diameter throughout its entire length. This casing 2 is provided with an inturned flange 3 at one end and with a plurality of screw threads 4 at the opposite end. Suitable beads 5 are formed exteriorly of the casing near each end but spaced inwardly therefrom, and are designed to limit the in-

ward movement of the caps 6 and 7 as clearly shown in Fig. 1.

Slidable in the casing 2 is the cylindrical soap container 8, one end of which is provided with the relatively thick inturned flange 9 having formed therein the screw threads 10 with which the threaded plug 11 having the knurled flange 12 formed at its outer end, cooperates. This plug 11 is designed to close the opening in the end of the soap container 8 and also form a thumb piece on which pressure is applied when the brush is being used. The end of the container 8 opposite the flange 9 is provided with the inturned flange 13 which is arranged to form a valve seat for the plug valve which will be more fully hereinafter described.

Extending into the threaded end of the casing 2 is the plug 14 which carries the bristles 15 and which is recessed axially as at 16 to receive the end of the valve plug opposite the end within the soap container 8. Communicating with the recess 16 are the apertures 17 which form soap ducts to carry the soap from the interior of the plug to the bristles.

The valve plug hereinbefore referred to, is designated generally by the numeral 18 and comprises the cylindrical body 19 having formed at each end the flanges 20. One of the flanges is of sufficient diameter to fit within the recess 16, while the opposite flange forms a stop against which the washer 21 bears, and this flange 20 provides a valve which seats against the flange 13 hereinbefore referred to. Formed axially in the body 19 is a suitable chamber or recess 22 which communicates at one end with the apertures 17 as clearly shown in Fig. 2. Suitable openings 23 are formed laterally of the recess or chamber 22 and these openings are arranged diametrically opposite and are arranged to admit the liquid from the container 8 to the chamber when the device is in use.

The cover 6 for the bristle end of the brush is preferably perforated as at 24 in order to admit the air thereto and permit the same to dry.

It will be apparent from the foregoing that in use when it is desired to use the brush, the caps 6 and 7 are removed and pressure is applied to the plug 11, thus causing the inner container to slide toward the

bristle end of the brush against the pressure of the spring 25. This will bring the flange 13 of the container at a point beyond the lateral extremities of the transverse apertures 23 and permit a portion of the contents of the container 8 to enter the chamber 22 and pass into the passages 17 from whence the liquid enters the bristles of the brush. After the necessary amount of soap 10 has been obtained, the pressure is released from the plug 11 and it will be apparent that under the influence of the spring 25 the inner container 8 will return to its normal position illustrated in Fig. 2 and 15 continue the feeding of the soap therefrom. The brush may then be used in the usual manner and after the shaving process, may be cleaned and the caps 6 and 7 replaced, thus placing the brush in condition for 20 transportation without danger of leakage.

While in the foregoing there has been shown and described the preferred embodiment of this invention it is to be understood that such changes may be made in the combination and arrangement of parts as will fall within the spirit and scope of the invention as defined in the appended claims.

What is claimed is:

1. A fountain shaving brush of the character described including a casing, a soap container slidable in the casing, the soap container being provided with a filling opening at one end and an outlet opening at the opposite end, a valve slidably mounted in the outlet opening, said valve being provided with a chamber and having lateral openings communicating with the chamber, a bristle holder threaded in the end of the casing and being provided with apertures communicating with the chamber, and a spring to normally hold the container away from the bristle holder.

2. A fountain brush of the character described including a casing, a soap container 45 slidable in the casing, a bristle holder threaded into one end of the casing, bristles carried by the bristle holder, a valve carried by the bristle holder and extending into the

casing, said valve being provided with a chamber communicating with the bristle holder, said bristle holder being provided with apertures communicating with the bristles, the valve extending into the casing and being provided with a pair of transverse apertures communicating with the chamber, the casing being designed to slide downwardly over the valve and cover the opening to permit the contents of the container to flow into the chamber, and a spring to return the chamber to its normal closed position. 50 55 60

3. A fountain shaving brush of the character described including a casing having a flange formed at one end, threads formed at the opposite end of the casing, a container slidable in the casing, said container being provided with a filling opening at the flanged end of the casing, the container being arranged to abut the flange, a plug for closing the filling opening, an inturned flange at the end of the container opposite the filling end, a bristle holder arranged to be threaded into the casing, bristles carried by the bristle holder, the bristle holder being provided with apertures communicating with the bristles of the brush to admit soap 75 thereto, the bristle holder being recessed, a valve seated in the recess, said valve being provided with a chamber communicating with the apertures in the bristle holder, the valve also being provided with lateral openings communicating with the chamber, flanges at each end of the valve, one of said flanges limiting the outward movement of the container, the said container being arranged to slide downwardly on the valve to 80 85 permit the contents thereof to pass into the chamber through the lateral openings, and a spring to return the chamber to its normal closed position.

In testimony whereof I affix my signature 90 in presence of two witnesses.

ARTHUR WM. SKOWBO.
